UNITED STATES PATENT OFFICE.

FLAVIUS B. STIKER, OF BUFFALO, NEW YORK, ASSIGNOR OF ONE-HALF TO ARTHUR F. OLIVER, OF BUFFALO, NEW YORK.

WATER-HEATER.

1,087,088.

Specification of Letters Patent.

Patented Feb. 10, 1914.

Application filed November 16, 1911. Serial No. 660,582.

To all whom it may concern:

Be it known that I, FLAVIUS B. STIKER, a citizen of the United States, a resident of Buffalo, in the county of Erie and State of New York, have invented certain new and useful Improvements in Water-Heaters; and I do hereby declare the following to be a full, clear, and exact description of my invention, such as will enable others skilled in the art to which it appertains to make and use the same, reference being had to the accompanying drawings, and to figures of reference marked thereon, which form part of this specification.

15 Like figures of reference refer to like parts.

My invention relates to the simpler form of water heaters as used in cook stoves.

The objects of my invention are to provide a heating device which can be readily cleaned out when the same becomes clogged with scale and other matter as accumulates during the use of a city water supply and to so form such a device, that it can be cheaply manufactured, while being efficient as an absorbent of heat units which escape the usual form of heater made up of straight pipes and return bends. To accomplish these objects, I have devised a tubular metallic casting having a series of fins integral therewith and having the bends thickened in a manner to form a boss at each bend, in which there is a hole adapted to receive a screw-plug.

35 The details of construction of my device are illustrated in the accompanying drawings and are hereinafter described and what I claim is set forth.

Figure 1, illustrates a plan of my device 40 positioned in a stove. The top of the stove is shown broken away to expose said device to view. Fig. 2, is a sectional elevation of said device taken on the line X—X of Fig. 1. Fig. 3, shows a section of a heater using 45 square tubes.

In the figures, in Fig. 1, 1 is a portion of a cook stove having therein two gas burners 2 and 3. Above said burners is positioned my device made up of a tubular casting having 50 four parallel portions numbered respec-

tively 4, 5, 6 and 7. The portions 4 and 5 communicate through the bend 8, which is expanded into a boss 9 containing a screw-plug 10. The portion 5 communicates with the portion 6 through the bend 11 having a 55 boss 12 and a screw-plug 13. Connecting the portions 6 and 7 is the bend 14 which has a boss 15 containing a screw-plug 16. Across all four of the parallel portions 4, 5, 6 and 7 and integral therewith, are the fins 17, 17, 60 17, a part of which with some of the parallel portions are broken away to better show the burner 3 below the same. The extremities of the portions 4 and 7 are each expanded into the respective bosses 18 and 19 adapted 65 to receive the pipes 20 and 21.

In Fig. 2, parts similar to parts shown in Fig. 1 are similarly numbered.

In Fig. 3, a fin is marked 22 as surrounding two square tubes 23 and 24 integral 70 therewith.

In operation, water coming from the pipe 20 finds its way into the portion 4, the bend 8, the portion 5, the bend 11, the portion 6, the bend 14, and the portion 7, in succession 75 into the pipe 21, the pipes 20 and 21 being connected with a reservoir and circulating system not shown, but of the usual construction. During the circulation of water just described, the heat produced by the burners 80 2 and 3 is absorbed through the exposed areas of the device including the greatly augmented area of the same in the fins.

In manufacturing these devices I find that the method of casting the same entirely 85 of one piece, exclusive of the said plugs, is very practical and cheap, allowing me to compete in price with the ordinary "coil" made up of straight pieces of pipe and return bends and other fittings; while my device 90 requires less fuel consumption to heat a given quantity of water a given temperature and allows of easy cleaning, which is important in maintaining the efficiency of my device.

Other heat producers than those above referred to may be used in connection with my device.

Having described my invention, I claim,
A water heating device comprising a tu- 100

bular metallic casting having a continuous bore in said casting and having a plurality of parallel portions with transverse fins integral therewith, any two adjacent parallel portions being in continuous tubular connection by means of a bend portion integral therewith, and a plug in screw-threaded en-

gagement with said bend portion, the free ends of said casting being adapted for tight pipe connections, substantially as set forth. 10

FLAVIUS B. STIKER.
